UNITED STATES PATENT OFFICE.

ALEXANDER L. STRAUS, OF BALTIMORE, MARYLAND, ASSIGNOR TO BALTIMORE PROCESS COMPANY, OF BALTIMORE, MARYLAND, A CORPORATION OF DELAWARE.

PROCESS FOR MAKING A NON-ALCOHOLIC BEVERAGE.

14,391.

Specification of Reissued Letters Patent. Reissued Nov. 6, 1917.

No Drawing. Original No. 1,223,121, dated April 17, 1917. Serial No. 150,329, filed February 23, 1917.

Application for reissue filed August 4, 1917. Serial No. 184,529.

To all whom it may concern:

Be it known that I, ALEXANDER L. STRAUS, a citizen of the United States, residing at Baltimore city, State of Maryland, have invented certain new and useful Improvements in Processes for Making a Non-Alcoholic Beverage, of which the following is a specification.

This invention relates to an improved

10 process for treating alcoholic beer, and converting such beer into a non-alcoholic beverage having substantially the same properties and elements save the alcohol which has been eliminated.

15 In carrying out my process I use beer of the regular alcoholic character.

In order that the process may be thoroughly understood, and for purposes of describing the same, let it be assumed that

20 the quantity processed in a single operation is one hundred barrels; this quantity is boiled in a brewer's kettle until all the alcohol is evaporated and eliminated.

The water in the beer which has also been 25 evaporated in the boiling operation in the evaporation and elimination of the alcohol is restored by adding to the boiled product heated water equivalent to the quantity evaporated.

30 The boiling operation changes the character of the beer, and to effect a restoration of this character is the object of this process.

When the boiling operation is nearing its 35 close, I add to every ten barrels of the product beverage one pound of salt, and a half hour before the boiling operation is completed I add one fifth of a pound of hops and two ounces of gum arabic per

40 barrel of the boiling beverage. I next add one and three fourth pounds of granulated sugar per barrel of the beverage or any other equivalent sweetening material, and I next add to the entire beverage product

45 now being boiled, and ten minutes before the boiling operation is completed, three pounds of concentrated hops, concentrated hops being of an entirely different character from ordinary hops in their action in

the beverage, in that concentrated hops are 50 pure hops, in which the dirt, seed and all impurities and foreign matter have been removed, and thus prevent turbidity in the finished product and also add to its keeping qualities.

55 The temperature of the beverage product is now rapidly reduced to approximately four degrees centigrade, preferably by running it over a Baudelot cooler; I next add to the beverage while in the process of being cooled, an agent to restore the bitter, pungent taste of the original beer, and to this end I supply one-half to one ounce of liquid quassia per barrel of the beverage.

This liquid quassia, I prefer to produce by 60 taking one ounce of commercial quassia and

boiling it in a sufficient quantity of water to produce sixteen ounces of liquor, and I then add one half to one ounce of this liquor thus obtained, per barrel of the beverage 70 while the beverage is being cooled in the Baudelot cooler. From the cooler the beverage is run into a chipcask, and while in the chip-cask I add finings in the manner usual with the ordinary brewing of beer; 75

I also add a suitable quantity of chill proofing preparation, preferably a pepsin compound known to the trade as "caluperline."

While the beverage is in storage I add a suitable preservative preferably in the form 80 of four commercial size tablets of meta-bisulfite of potassium, known to the trade as "K. M. S." or "kalium meta-sulfite tablets" per barrel.

After the beverage product has been in storage from two to five 85 days, it is then filtered and carbonated at from 15 to 16 pounds carbonic gas pressure and is then ready for the market.

The process in detail involves the following:—

90 First: Beer that has been brewed from malt, hops and cereals forms the basis.

Second: The elimination of all alcohol, and some of the water by boiling the beer.

Third: The restoration of the water by 95 adding a quantity of heated water approximating that which was evaporated by the boiling of the beer.

Fourth: Adding one pound of salt to every ten barrels of the beverage product.

Fifth: Adding one fifth of a pound of hops and two ounces of gum arabic per 5 barrel of the beverage product.

Sixth: Adding one and three fourth pounds of granulated sugar per barrel.

Seventh: Adding to the entire beverage product approximately ten minutes before 10 the boiling operation is completed three pounds of concentrated hops.

Eighth: Rapidly reducing the temperature of the beverage to approximately four degrees centigrade.

15 Ninth: Adding one half to one ounce of quassia liquor per barrel.

Tenth: Adding the usual quantity of finings.

Eleventh: Adding a chill proof preparation.

Twelfth: Adding four commercial size meta-bisulfite of potassium tablets per barrel.

Thirteenth: Storing the beverage from 25 two to five days.

Fourteenth: Filtering and carbonating the beverage under 15 to 16 pounds carbonic acid gas pressure.

Fifteenth: Drawing off into packages 30 ready for the market.

By the above described process a non-alcoholic beverage is produced from ordinary beer having substantially the taste, appearance, nutritious or extractive matter and 35 other qualities of beer, save that it is non-alcoholic, in that it does not contain alcohol.

It is obvious that those skilled in the art 40 may vary the proportions, the ingredients, as well as the details of the procedure above set forth without departing from the spirit of the invention, and therefore, I do not wish to be limited to the above disclosure except as may be required by the claims.

What I claim is:—

45 1. The steps in a process of making a substantially non-alcoholic beverage from a fermented malt liquor containing alcohol which comprises eliminating substantially all the alcohol present from said liquor, and adding 50 to the residue suitable quantities of salt, sugar and hops, substantially as described.

2. The steps in a process of making a substantially non-alcoholic beverage from a fermented malt liquor containing alcohol which 55 comprises evaporating substantially all the alcohol present and a portion of the water, and adding to the residue thus obtained suitable quantities of water, salt, sweetening material and hops, substantially as described.

60 3. The steps in a process of making a substantially non-alcoholic beverage from a fermented malt liquor containing alcohol which

comprises evaporating substantially all the alcohol present and a portion of the water, 65 and adding to the residue thus obtained suitable quantities of water, salt, sweetening material, hops, and an agent to impart a bitter taste to the beer, substantially as described.

4. The steps in a process of making a substantially non-alcoholic beverage from a fermented malt liquor containing alcohol which 70 comprise evaporating substantially all the alcohol present and a portion of the water, and adding to the residue thus obtained suitable quantities of water, salt, sweetening material, hops, an agent to impart a bitter, 75 pungent taste to the beer, and a foam producing material, substantially as described.

5. The steps in a process of making a substantially non-alcoholic beverage from a fermented malt liquor containing alcohol which 80 comprise evaporating substantially all the alcohol present and a portion of the water, and adding to the residue thus obtained suitable quantities of water, salt, sweetening material, hops, quassia, a foam producing material, finings and a chill proofing material, 85 substantially as described.

6. The steps in a process of making a substantially non-alcoholic beverage from a fermented malt liquor containing alcohol which 90 comprise evaporating substantially all the alcohol present and a portion of the water, and adding to the residue thus obtained suitable quantities of water, salt, sweetening material, hops, and a preservative compound, 95 substantially as described.

7. The steps in a process of making a substantially non-alcoholic beverage from a fermented malt liquor containing alcohol which 100 comprise evaporating substantially all the alcohol present and a portion of the water, and adding to the residue thus obtained suitable quantities of water, salt, sweetening material, hops, a preservative compound, and 105 quassia, substantially as described.

8. The steps in a process of making a substantially non-alcoholic beverage from a fermented malt liquor containing alcohol which 110 comprise evaporating substantially all the alcohol present and a portion of the water, and adding to the residue thus obtained suitable quantities of water, salt, sweetening material, hops in a concentrated form, quassia, 115 meta-bisulfite of potassium; and suitably carbonating the product.

9. A process for making a non-alcoholic beverage from fermented malt liquor, consisting in boiling the malt liquor to remove the alcohol and some of the water, adding heated water to the amount of that evaporated; adding salt, hops, gum arabic and sugar during the boiling operation; adding concentrated hops near the close of the boiling operation; gradually reducing the tem- 120

perature to approximately 4° C.; adding one half to one ounce of liquid quassia per barrel; adding a suitable quantity of finings while the beverage is being cooled; adding **6** chill proof preparation; adding four commercial size tablets of meta-sulfite of potassium per barrel while the beverage is in storage; permitting the beverage to remain in storage from two to five days; filtering and

carbonating the beverage, and drawing it off **10** in packages for the market.

In testimony whereof I affix my signature in the presence of two witnesses.

ALEXANDER L. STRAUS.
